(57) **CLAIM**

The ornamental design for a food wrap dispenser, as shown and described.

DESCRIPTION

FIG. 1 is a top perspective view of a food wrap dispenser, showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken lines illustrate both parts of the article and symbolic breaks in the length and width of the article, none of which form part of the claim. Interior surfaces of the article within the dot-dash boundary form no part of the claimed design.
